W. H. McGINLEY,

CAR REPLACER.

APPLICATION FILED DEC. 11, 1920.

1,378,180.

Patented May 17, 1921.

UNITED STATES PATENT OFFICE.

WILLIAM H. McGINLEY, OF PLEASANT BEACH, NEW YORK.

CAR-REPLACER.

1,378,180.

Specification of Letters Patent.

Patented May 17, 1921.

Application filed December 11, 1920. Serial No. 429,988.

To all whom it may concern:

Be it known that I, WILLIAM H. McGINLEY, a citizen of the United States, and resident of Pleasant Beach, in the county 5 of Onondaga, in the State of New York, have invented new and useful Improvements in Car-Replacers, of which the following, taken in connection with the accompanying drawings, is a full, clear, and exact de-
scription.

This invention relates to certain improvements in car replacers of the class set forth in my pending application Serial No. 332,245, filed October 21, 1919, and allowed 15 under date of November 5, 1920, except that the leader plate, while removable from the base plate, is held against lateral swinging movement and the final replacement of the car wheels, after riding up the inclined 20 leader plate, is effected by means of a switch point which is movable into and out of registration with each of the guide rails of said leader plate, to permit the replacer to be used at the inside or outside of either 25 rail of the track.

It is important that the heel of the switch point be positioned in a definite relation to the ball of the rail when the replacer is set 30 for replacing the car upon the track, and one of the objects of the invention is to provide a gage which is reversible for engagement with either side of either rail, to hold the base plate, with the switch point 35 thereon, a predetermined distance from the ball of the rail.

Another object is to provide means for transmitting motion from the gage plate to the switch point to shift the latter from one 40 extreme to the other as the gage plate is reversed and to lock said switch point in its adjusted position.

A further object is to provide means for holding the replacer in operative position 45 against lateral movement relatively to the rail.

Other objects and uses relating to specific parts of the replacer will be brought out in the following description:

50 In the drawings:

Figure —1— is a perspective view of a portion of one of the rails of a track and my improved replacer operatively connected thereto.

55 Fig. —2— is a longitudinal vertical sec-

tional view of the switch and underlying portions of the base.

Fig. —3— is a horizontal sectional view of the switch point, showing its operating cam in top plan.

Figs. —4—, —5— and —6— are transverse vertical sectional views taken, respectively, on lines 4—4, 5—5 and 6—6, Fig. —1—.

As illustrated, this car replacer comprises 65 a base plate —1—, a leader plate —2—, a switch point —3—, means for operating the switch point and suitable means for clamping the base plate to either of the rails, as —A—, of the track.

The base plate —1— is elongated lengthwise of the track and tapered toward one end, which will hereinafter be termed the heel of the plate, the main body of the base plate being provided with a substantially 70 flat upper face —4—, which is inclined from the wider end toward the heel, for receiving and supporting the leader plate —2— in a parallel inclined plane.

The opposite sides of the intermediate 75 portion of the main body are provided with laterally projecting spacing lugs —5— for engaging the web of the rail —A— and holding the edge of the base plate a predetermined distance therefrom. The front end of the base plate —1— is provided with a serrated lower gripping face —6—, adapted to rest upon one of the ties, as —B—, to hold the plate against slipping during the 80 replacing of the car thereby.

The rear end of the heel of the plate is provided with a recess —7— in its lower side for receiving a gage plate —8— which is pivoted to the under side of said base 85 plate for horizontal swinging movement into and out of engagement with the web of the rail —A—, to hold the adjacent end of the base a predetermined distance from the rail, said gage plate being provided with 90 pendent flanges —9— and —10— at opposite ends thereof, for engagement, respectively, with the lower flange of the rail —A— and with the adjacent tie —B—, as

shown more clearly in Fig. —4—, thereby 105 constituting additional support for the heel of the base plate upon the tie and rail.

The leader plate —2— extends lengthwise of and upon the greater portion of the main body of the base plate and is also 10

tapered from its front end to its rear end to correspond to the taper of said base plate and is provided along its opposite lengthwise edges with raised flanges —11— converging rearwardly from the front end of the leader plate to the front end of the switch point —3—, for engaging the flange of the car wheel and gradually deflecting the wheels of the truck toward the rails, as they ride forwardly and upwardly along the upper face of the leader plate.

The front ends of the base plate —1— and leader plate —2— are comparatively thin or shallow vertically and are, therefore, of considerable less depth than the vertical height of the frame, to enable the wheels of the truck to enter freely and easily upon the leader plate, as the car is propelled forwardly in the act of replacing the same upon the track. The inclination of the upper faces of the base plate —1— and leader plate —2— is such that the combined depths or vertical thickness of the rear end of the leader plate and underlying portion of the base plate are considerably greater than the height of the rail, or at least slightly greater than the combined depth of the rail and radial depth of the flange of the wheel, so that the upper faces of the rear ends of the flanges —11— will be disposed in a horizontal plane a distance above that of the top of the rail greater than the depth of the flange of the wheel, to allow the flange of the wheel, which is displaced at the outside of the track, to ride over the ball of the adjacent rail, it being understood that the vertical depth of the flanges —11— is slightly greater than the flange —a— of the wheel.

The rear end of the base plate —1— is also provided with a pair of flanges —12— along opposite edges thereof, to form continuations of the flanges —11—, except that they are somewhat narrower transversely, to form recesses —13—, for receiving the free end of the switch point —3—, so that when the switch point is shifted into either recess, its inner face will form a continuation of the inner face of the corresponding rib —11—, thereby assisting said ribs in deflecting the wheels of the truck toward the respective rails, as they move along and upon their respective leader plates —2—.

This leader plate —2— is removably mounted upon the inclined upper face —4— of the base plate —1—, to permit it to be removed and used individually on paved streets and in other places where it might be of use in assisting to bring the wheels of the car into closer or proper relation to their respective rails, but when used on the base plate is normally held in operative position by one or more studs —14— and cotter keys or pins —15—, said studs being, in this instance, formed integral with the

underside of the leader plate and are adapted to enter apertures —16— in the base plate, as shown more clearly in Fig. —6—.

The front ends of the flanges —12— on the base plate —1— extend upwardly above the adjacent ends of the inclined face —4— a distance corresponding approximately to the height of the flanges —11—, while the rear ends of said flanges —12— are inclined downwardly and rearwardly and terminate on a substantially flat platform —17— on the rear end of the base plate some distance forwardly from the rear end thereof, to allow the wheel, which may be riding thereon, to gradually descend to the ball of the rail for replacement, after it has been urged or deflected laterally by one of the flanges —11— and switch point —3— sufficiently to align with its rail.

An upright pivotal pin —18— is centrally journaled in the rear end of the base plate —1— or in the platform —17— and extends beyond the lower and upper faces thereof, the portion of the pivotal pin immediately below the platform —17— being of annular cross-section for engaging a similar formed aperture —19— in the gage plate —8— which is held against axial displacement from said pivotal pin by a cotter key —20—, the portion of the pin just above the upper face of the platform —17— being also of angular cross-section and engaged in a similarly formed aperture —21— in a cam member —22— which rests upon the upper face of the platform —17— to turn with the pivotal bolt —18—.

The switch point —3— is journaled at its rear end upon the upper end of the pivotal bolt —18— directly over the cam —22— to permit its front point to swing laterally into and out of alignment with either of the ribs —11—, the upper end of the pivotal bolt —18— being enlarged to fit into a corresponding recess —23— in the upper face of the switch point —3—, to hold the latter against upward displacement.

The intermediate portion of the switch point —3— is extended downwardly some distance below the upper face of the cam —22— and is provided with opposite abutments —24— at the rear of the cam and in close proximity thereto, for engagement by radial projections —25— on opposite sides of said cam, as the latter is rocked in reverse directions for shifting the switch point to and locking it in either of its extreme positions.

It is now apparent from the foregoing description that the gage plate —8— may be rotated about the axis of the pivotal pin —18— through an arc of approximately 180°, to permit the replacer to be used at the inner or outer side of either rail and that this rotary movement will be transmit-

ted by the pivotal pin to the cam —22— and that by spacing the projections —25— a suitable distance apart the reversal of the gage plate —8— from one position to another will cause them to engage the abutments —24— and thereby shift and lock the switch point to and in either of its extreme positions.

That is, the angular movement of the cam disk —22— is the same as that of the gage plate —8—, while the arc of movement of the switch point —3— is considerably less, and in order that the gage plate and cam may be free to move through an entire arc of 180° and, at the same time, to shift and lock the switch point in its shifted position, the shoulders or projections —25— are arranged at an angle of considerably more than 180° corresponding to the distance between the abutments —24— and to the angular movement of the switch point.

It, therefore, follows that when the gage plate —8— is adjusted to one position at right angles to the longitudinal center of the base plate —1—, one of the shoulders —25— will have engaged and shifted the switch point into registration with one of the flanges —11— and that, when the gage plate is reversed, the other shoulder —25— will have engaged and shifted the switch point into registration with the other flange —11— and that in both positions of adjustment of the gage plate, the switchpoint will be firmly held in its adjusted position.

Suitable means is provided for clamping the base plate —1— to either of the rails and, for this purpose, the base plate is provided with a transverse opening —26— through which is passed a locking bolt —27—, having one end provided with a hook-shaped extremity —28— for interlocking engagement with the ball of the rail, while the other end is provided with a transverse opening —29— for receiving a wedge key —30— which engages the adjacent upright face of the base plate to coöperate with the hook-shaped extremity —28— in holding the base plate in fixed relation to the rail —A—.

It is evident, however, that this clamping device may be reversed relatively to the base plate, to permit the replacer to be used either at the inside or at the outside of either rail and that by pivoting the switch point —3— in the longitudinal center of the base plate as well as that of the leader plate, either edge thereof may be used as a continuation of either of the flanges —11— for engaging the flange of the wheel and crowding both wheels of the truck over and upon their respective rails as they are impelled up the inclined ways of their respective leader plates, it being understood that a pair of these replacers are used simultaneously to replace the two wheels of the same axle upon their respective rails, one of them

being clamped to the inside of the rail, while the other is clamped to the outside, according to the displaced positions of the wheels.

For example, the replacer at the outer side of the rail would be set to allow the tread of the corresponding wheel to ride upon the rib —11— nearest the rail, while the flange of the same wheel would travel in the space between the rib and rail and the switch point would be shifted into registration with the opposite rib —11—. On the other hand, the other replacer would be set a similar distance from the inner side of its rail to permit the flange of the adjacent wheel to ride up the inclined face of the leader plate between the ribs —11—, so that its tread portion may overhang the rib nearest the rail as the wheel approaches the top of the incline, during which travel, the inner face of the wheel flange will ride against the inner face of the flange —11— farthest from the corresponding rail and will, therefore, gradually crowd both wheels toward the rails as they are elevated above the balls thereof when reaching the top of the incline, it being understood that the switch point for the replacer at the inner side of the rail is registered with the rib —11— farthest from the rail and serves to give the final crowding effect of the adjacent wheel over and upon its rail, at which time, the other wheel will be registered with the adjacent rib, thereby replacing both wheels simultaneously.

In order that this operation may be clearly understood, Fig. —4— may be regarded as showing the replacer at the inner side of one rail, while Fig. —5— may be considered as showing a companion replacer at the outer side of the rail, portions of the car wheels being shown by dotted lines in the positions which they would assume when reaching the top of the incline of the replacer, about ready to leave the rear end of said replacer for shifting the wheels on to their respective rails as the one between the rails continues to ride along and against the side of the switch point nearest the corresponding rail, the rear ends of the ribs or flanges —12— being inclined downwardly at the sides of the switch point, to allow the wheels to gradually drop onto the track. During this replacing operation, the inner rib or flange —11— of the replacer at the inner side of the rail and the switch point —3— registering with said rib actually constitutes the means for crowding the flange of the corresponding wheel gradually toward its rail until the tread of that wheel overhangs the ball of the rail, as shown by dotted lines in Fig. —4—, at which time the flange of the other wheel on the same axle will have been shifted or drawn in the same

direction until it overhangs the ball of the adjacent rail, so that, as the car continues to move rearwardly over the replacer, its wheels which have been riding up the incline on the replacer will be gradually brought to position to drop on the track when leaving the rear end of the replacer.

It is now clear that the replacers for the inside and outside of the rails are identical 10 and may be interchanged or used at either side of either rail and that, while the construction shown is particularly efficient in speedily replacing the car upon the track, it is evident that various parts thereof may 15 be altered without departing from the spirit of this invention.

What I claim is:

1. In a car replacer in combination with a rail, a base section supported along one 20 side of the rail and having a longitudinally inclined upper face, a leader plate resting on said inclined face and provided with raised ribs along its opposite edges in spaced relation and converging toward one end, 25 means for clamping the base to the rail and a switch point pivoted to the base and movable into and out of registration with each of said ribs.

2. A car replacer comprising a base, having a longitudinally inclined upper face, a 30 switch point pivotally mounted on the base to swing horizontally, a gage plate rotatably mounted on the base for engaging the rail of the track and holding the replacer 35 a definite distance therefrom and means for transmitting rotary motion from the gage plate to the switch point.

3. In combination with the rail of a track, a car replacer along side of the rail having 40 a longitudinally inclined upper face, an upright spindle journaled on the base, a switch point mounted to the spindle and extending toward the lower end of the inclined face, a gage plate also secured to the spindle to 45 rotate therewith for engagement with the rail and means for transmitting rotary motion from the gage plate to the switch point.

4. In combination with the rail of a track, a car replacer along side of the track and 50 provided with a longitudinally inclined upper face, a spindle journaled on the base at the higher end of the incline, a gage plate secured to the spindle to rotate therewith for engagement with the rail, a switch point 55 loosely mounted on the spindle and extending therefrom toward the lower end of the incline and movable laterally from side to side of the base, and means for transmitting rotary motion from the gage plate to the 60 switch point.

5. In combination with the rail of a track, a car replacer extending lengthwise of the track, means for holding the replacer a definite distance from the rail, including 65 bosses projecting from opposite sides of the

replacer for engaging the web of the rail, said replacer having raised ribs along its opposite longitudinal edges in spaced relation and converging in one direction.

6. A car replacer having an inclined upper surface and spaced lengthwise ribs converging toward the higher end of the incline, a switch point pivoted at one end and having its other end movable into and out of registration with each of the ribs, 75 and a gage plate for holding the replacer a definite distance from the rail.

7. A car replacer having an inclined upper surface and spaced lengthwise ribs converging toward the higher end of the incline, a switch point pivoted at one end and having its other end movable into and out of registration with each of the ribs, and a gage plate for holding the replacer a 80 definite distance from the rail, said gage plate being reversible for engaging the rail at either side of the replacer.

8. A car replacer having an inclined upper surface and spaced lengthwise ribs converging toward the higher end of the incline, a switch point pivoted at one end and having its other end movable into and out of registration with each of the ribs, and a gage plate for holding the replacer a definite distance from the rail, and connections 85 between the gage plate and switch point for holding the latter in one of its shifted positions.

9. A car replacer comprising a base having a longitudinally inclined upper face 90 and spaced lengthwise ribs converging up the incline, a switch point pivoted at one end to the base and having its opposite end movable into and out of registration with each of the ribs and a clamping member passed through the base beneath the switch point for clamping the replacer to a rail.

10. A car replacer comprising a base having an inclined upper face, a leader plate 110 detachably mounted upon the inclined face and provided with spaced lengthwise ribs converging up the incline, a switch point pivotally mounted upon the base at the higher end of the leader plate and movable 115 into and out of registration with each of the ribs, and means for clamping the base to a rail.

11. A car replacer comprising a base having a longitudinally inclined upper face, a 120 leader plate mounted on the inclined face and provided with spaced lengthwise ribs converging up the incline, a gage plate mounted on the under side of the heel of the base for engaging a rail and a clamping member passed through the base in front of the gage plate for clamping the replacer to the rail.

12. A car replacer comprising a base having a longitudinally inclined upper face, a 125

leader plate mounted on the inclined face and provided with spaced lengthwise ribs converging up the incline, a gage plate mounted on the under side of the heel of 5 the base for engaging a rail and a clamping member passed through the base in front of the gage plate for clamping the replacer to the rail, and a switch point mounted on the wheel of the base and extending for-

wardly over the top of said clamping member and movable into and out of registration with each of said ribs.

In witness whereof I have hereunto set my hand this 30th day of November 1920.

WILLIAM H. McGINLEY.
